UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

INTERRUPTER FOR IGNITION DEVICES.

1,327,344.

Specification of Letters Patent.

Patented Jan. 6, 1920.

Application filed March 27, 1918. Serial No. 225,030.

To all whom it may concern:

Be it known that I, CHARLES THOMAS MASON, a citizen of the United States, residing at Sumter, in the county of Sumter 5 and State of South Carolina, have invented certain new and useful Improvements in Interrupters for Ignition Devices, of which the following is a specification, reference being had to the accompanying drawing.

10 The invention relates to new and useful improvements in interrupters for ignition devices and more particularly to an interrupter for breaking the primary circuit in a high tension ignition system for producing 15 a current in a secondary circuit for sparking purposes.

In my co-pending application, Serial Number 223,164, filed March 18, 1918, I have shown and described a method and ignition 20 mechanism for carrying out the method wherein the primary circuit of a high tension ignition system is interrupted by the separation of the same pair of contacts at each spark interval and wherein the resistance of said contacts when closed is reduced 25 by other contacts arranged in multiple therewith and which are timed so as to open before and close after the other contacts which interrupt the primary circuit.

30 The present invention is directed to improvements in an interrupter for an ignition mechanism such as set forth in my prior application and an object of the present invention is to provide an interrupter which 35 shall be durable in construction, of few parts, positively operated and constructed so that the various parts may be readily disassembled for adjustment and for repair.

In the drawings which show by way of 40 illustration one embodiment of the invention:

Figure 1 is a front view of an interrupter with the cap plate removed;

Fig. 2 is a vertical sectional view through 45 the interrupter;

Fig. 3 is a section on the line 3—3 of Fig. 1;

Fig. 4 is a section on the line 4—4 of Fig. 1;

50 Fig. 5 is a view showing more or less diagrammatically the interrupter with the cam positioned for separating one pair of contacts;

Fig. 6 is a similar view but showing the

cam position for separating both pairs of 55 contacts;

Fig. 7 is a view showing in front elevation a modified form of means for separating the stationary contact points.

The invention is embodied broadly in an 60 interrupter for breaking the circuit of a high tension ignition system which includes two pairs of contacts, one of which is of higher conductivity than the other. One contact in each pair is fixed while the other 65 contact of each pair is carried by a shiftable lever, which is moved by a cam on the main shaft of the magneto or the generator when the interrupter is applied to such ignition system. One of these contacts carried by the shiftable lever is mounted 70 yieldingly thereon and held so that in the movements of the lever, one pair of contacts will be separated and while they are separated the other pair of contacts will 75 open and close. These contacts are also so arranged that the contacts of relatively high conductivity are opened first and while they are opened the contacts of relative low conductivity are opened and closed so that the 80 circuit is always broken by the contacts of relative low conductivity and the contacts of relative high conductivity serve principally to reduce the resistance in the primary circuit caused by these contacts of low 85 conductivity and thus enable the magneto to build up its current and produce a strong and efficient current for sparking purposes. The shifting lever is disposed so that the 90 movable contacts are at one side of the operating cam, while the contact member carried by the lever which co-operates with the cam is located substantially at the other side thereof. The yielding contact carried by the shiftable lever is fixed to a spring which 95 is secured to the lever by screws so that it may be readily removed from the interrupter. The lever is provided with a bronze sleeve bushing which is secured thereto by spinning over the end of the sleeve.

100 Referring more in detail to the drawings I have shown my invention as embodied in an interrupter including a supporting base 1. Attached to this supporting base is a cap or casing 2 which incloses the parts of the interrupter. The base 1 is mounted on the magneto and is connected with the magneto ignition system so that it may be swung

for advancing and retarding the spark. The movements of the base are brought about through an arm indicated at 3. Extending through the base is a rotating shaft 4 which carries an operating cam 5. My interrupter includes two pairs of contacts, one pair as indicated at 6 and 7 and the other at 8 and 9. The movable contacts 7 and 9 are carried by a lever 10 which is fulcrumed on a projecting pin 10^a carried by the base 1 (see Fig. 3). The lever 10 is angular in shape and the two parts of the lever are arranged at an acute angle to each other. At the opposite end of the lever 15 from the contacts 7 and 9 is a fiber block 11 which is adapted to engage the cam 5. The cam 5 has two high points 12 and 13 which are similar in shape. The fiber block 11 is substantially diametrically opposite the contact members 7 and 9. The high point on the cam will engage this fiber block 11 and swing the lever on its fulcrum so as to move the end of the lever carrying the contacts away from their coöperating contacts 6 and 20 8. A spring 14 is attached to an abutment 15 and also to the lever 10 and this spring normally operates to swing the lever so as to close the contacts. The part of the cam 5 between the high points is of such diameter that the movement of the lever through 25 the action of the spring 14 is limited by the contacts.

The contacts 6 and 8 are fixed; that is, they have no movement during the normal 30 operation of the interrupter. These contacts are carried by a supporting metal bracket 16. The metal bracket 16 is mounted on a block of insulating material 17. This metal bracket and the insulating block 40 on which it rests fit in a rectangular recess in the base 1 proper of the interrupter and are held therein by suitable screws 18 passing through the base from the back side thereof and threaded into the metal bracket 45 16. The screws are insulated from the base 1. The contact point 6 as above noted is formed of tungsten and is inserted in the end of a screw 22 and welded therein. The screw 22 has a threaded connection with the 50 metal bracket 16. The bracket is split and a screw at 22^a by drawing the split sections of the bracket together clamps the screw 22 and firmly holds it in adjusted positions. The contact point 8 is similarly formed as a 55 part of the screw 23 which is likewise threaded into the metal bracket 16 and is held in adjusted positions by a screw 23^a.

The primary of the generating coil is indicated at 20 in the drawings and this 60 primary is attached to the metal bracket at 21 and thus forms a connection with the contacts 6 and 8. In Figs. 1 to 6 inclusive I have shown the metal bracket 16 as formed in one piece. In Fig. 7 of the drawings I 65 have shown a slightly modified form of the

bracket and it is formed in two sections indicated at 16^a and 16^b. The two sections are separated from each other and as they are independently connected to the insulating base 17 and the base 1 of the magneto 70 proper, these bracket sections may be connected through independent lines with a primary circuit if desired. The construction of the metal bracket so far as supporting the fixed contacts 6 and 8 is concerned 75 is similar to that described above.

The lever 10 is of sectional construction. Said lever is formed in two parts indicated at A and B. Each part is stamped up from metal in channel form and they are so constructed that the part A fits within the channel of the part B. The fiber block 11 fits within the channel of this part B and is secured therein by suitable rivets 24 and 25. At the fulcrum point of the lever there 80 is a center block 26. The two parts of the lever are secured together by a bronze sleeve bushing 27 which extends through the two parts A and B of the lever and through the center block 26. The sleeve is formed with 85 a flange 28 at its inner end and is closed at its outer end. A washer 29 is placed on the outer end of the sleeve after which it is spun over the edge of the washer as indicated at 30. This firmly joins the two sections of the lever together and to the center block which fits within the section A. As a further means of rigidly securing the sections of the lever I may provide rivets 31. The sleeve bushing 27 freely engages the 90 pin 10^a and is held thereon by a flat spring arm 31 which is secured to the abutment 15 and has a depression in its outer end indicated at 32 in Fig. 2 of the drawings, which engages a rounded stud 33 on the end of the 95 sleeve 27. By releasing the spring 14 and lifting the arm 21 and drawing the same to one side, the entire lever may be removed.

The tungsten contact 7 is rigidly secured to a leaf spring 34 which extends into the 100 channel of the section B of the lever and is secured to this section of the lever by a bolt 35 which is threaded into a metal block 36. The spring 14 is secured to the center block 26 by a screw 36^a.

In the operation of my device let us assume that the cam 5 is rotating in a clockwise direction. As soon as the high point 12 engages the fiber block 11 it will shift the lever. The spring 34 is normally out of 110 contact with the section A of the lever when the contacts are closed as shown in Fig. 1. The first shifting movement of the lever as indicated in Fig. 5 will separate the contacts 8 and 9, while the contacts 6 and 7 115 still remain closed. A continued movement of the shaft brings the high point of the cam entirely underneath the fiber block 11 and this will shift the lever to a sufficient extent to separate the contacts 6 and 7. 120 125

As the cam 5 continues to move, the contacts 6 and 7 will close first, after which the contacts 8 and 9 will close. It will thus be seen that I have provided a construction wherein 5 the primary circuit is broken at each spark interval by the contacts 6 and 7 and the circuit is also closed by these contacts. Inasmuch as these contacts are made of tungsten which is a metal of relatively low conductivity there will be little or no sparking. The contacts 8 and 9 when they are closed, being in multiple with the contacts 6 and 7 and of relative high conductivity, will reduce the resistance in the primary circuit 10 which the contacts 6 and 7 would otherwise establish. Both pairs of contacts are opened and closed at each spark interval, but one pair open previous to the other and remain open until the circuit has been broken and 15 again closed by the other pair.

While I have described my improved circuit breaker as particularly adapted for interrupting the primary circuit of the magneto and also described my operating lever 20 as carrying contacts formed of metal of relatively different conductivities, it will be understood that from certain aspects of the invention my improved interrupter and parts thereof may be used in connection 25 with ignition systems of other types.

Having thus described my invention, what I claim as new and desire to secure by Letters Patent is:

1. An interrupter mechanism for ignition 30 systems comprising a pair of main contacts, one of which is movable for breaking a circuit to produce an ignition spark, a pair of auxiliary contacts in multiple with said main contacts and one of which is movable, 35 said auxiliary contacts being timed so as to open before and close after said main contacts, a lever carrying the movable contacts, said lever being fulcrumed intermediate its ends and carrying the contacts at one end 40 thereof, a fiber block at the other end of said lever from the contacts and a cam adapted to engage the fiber block for moving 45 said lever.

2. An interrupter mechanism for ignition 50 systems comprising a pair of main contacts, one of which is movable for breaking a circuit to produce an ignition spark, a pair of auxiliary contacts in multiple with said main contacts and one of which is movable, 55 said auxiliary contacts being timed so as to open before and close after said main contacts, a lever fulcrumed intermediate its ends and carrying said movable contacts at one end thereof, a fiber block at the other end 60 of said lever; a spring for moving the lever so as to normally hold the contacts in engagement and a cam engaging the fiber block for moving the lever in the opposite direction.

65 3. An interrupter mechanism for ignition

systems comprising a pair of main contacts, one of which is movable for breaking a circuit to produce an ignition spark, a pair of auxiliary contacts in multiple with said main contacts and one of which is movable, 70 said auxiliary contacts being timed so as to open before and close after said main contacts, a lever fulcrumed intermediate its ends, a cam coöperating with one end of the lever for moving the same, a spring for moving the lever in the opposite direction, means for rigidly securing one of the movable contacts to the lever, a spring carried by the lever and supporting the other contact.

4. An interrupter mechanism for ignition 80 systems comprising a pair of main contacts, one of which is movable for breaking a circuit to produce an ignition spark, a pair of auxiliary contacts in multiple with said main contacts and one of which is movable, 85 said auxiliary contacts being timed so as to open before and close after said main contacts, a lever carrying the movable contacts, means for operating the lever, a supporting pin for the lever, a bronze bushing rigidly 90 secured to the lever and engaging said pin for forming a bearing support for the lever.

5. An interrupter mechanism for ignition 95 systems comprising contacts, one of which is movable for breaking the circuit to produce an ignition spark, a lever supporting the movable contact, said lever being formed from two sections of metal stamped to channel form, one of which fits within the other, 100 a bronze bushing sleeve extending through the side members of both sections, said sleeve having a flange at one end thereof, and means at the other end thereof for holding the sections together, said sleeve also serving as the fulcrum bearing support for the lever. 105

6. An interrupter mechanism for ignition 110 systems comprising contacts, one of which is movable for breaking the circuit to produce an ignition spark, a lever supporting the movable contact, said lever being formed from two sections of metal stamped to channel form, one of which fits within the other, 115 a bronze bushing sleeve extending through the side members of both sections, said sleeve having a flange at one end thereof, and means at the other end thereof for holding the sections together, said sleeve also serving as the fulcrum bearing support for the lever, a center block through which said sleeve passes, said center block being located 120 within the channel of the inner section of the lever, a spring secured to said center block for moving said lever in one direction and a cam for moving the lever in the opposite direction. 125

7. An interrupter mechanism for ignition 130 systems comprising contacts, one of which is movable for breaking the circuit to produce an ignition spark, a lever supporting the movable contact, said lever being formed

from two sections of metal stamped to channel form, one of which fits within the other, a bronze bushing sleeve extending through the side members of both sections, said sleeve having a flange at one end thereof, and means at the other end thereof for holding the sections together, said sleeve also serving as the fulcrum bearing support for the lever, a center block through which said sleeve passes, said center block being located within the channel of the inner section of the lever, a spring secured to said center block for moving said lever in one direction and a cam for moving the lever in the opposite direction, a fiber block fitting within the channel in one section of the lever and adapted to engage the operating cam.

8. An interrupter mechanism for ignition systems comprising a pair of contacts, one of which is movable for breaking the circuit to produce an ignition spark, a lever carrying the movable contact, said lever being formed of two sections of metal stamped to channel form and one fitting within the other, a center block located within the inner section at the fulcrum point of the lever, a bronze bushing sleeve extending through openings in the side members of the sections of the lever and through the center block, said sleeve having a flange at its inner end and the outer end thereof being closed, a washer on the outer end of the sleeve, said sleeve being spun over the washer to hold the parts assembled and means for operating the lever.

9. An interrupter mechanism for ignition systems comprising a pair of contacts, one of which is movable for breaking the circuit to produce an ignition spark, a lever carrying the movable contact, said lever being formed of two sections of metal stamped to channel form and one fitting within the other, a center block located within the inner section at the fulcrum point of the lever, a bronze bushing sleeve extending through openings in the side members of the sections of the lever and through the center block, said sleeve having a flange at its inner end and the outer end thereof being closed, a washer on the outer end of the sleeve, said sleeve being spun over the washer to hold the parts assembled and means for operating the lever.

end of the sleeve, said sleeve being spun over the washer to hold the parts assembled, a pin on which said sleeve is mounted, a stud on the outer end of the sleeve, a yielding arm engaging said stud for holding the lever on said pin and means for operating the lever.

10. An interrupter mechanism for ignition systems comprising a pair of contacts, one of which is movable for breaking the circuit to produce an ignition spark, a lever carrying the movable contact, said lever being formed of two sections of metal stamped to channel form and one fitting within the other, a center block located within the inner section at the fulcrum point of the lever, a bronze bushing sleeve extending through openings in the side members of the sections of the lever and through the center block, said sleeve having a flange at its inner end and the outer end thereof being closed, a washer on the outer end of the sleeve, said sleeve being spun over the washer to hold the parts assembled, a pin on which said sleeve is mounted, a stud on the outer end of the sleeve, a yielding arm engaging said stud for holding the lever on said pin and means for operating the lever, said operating means including a cam, a fiber block secured within the channel of the lever and engaging said cam, a spring connected with said center block for normally holding the contacts in engagement.

11. An interrupter mechanism for ignition systems comprising a supporting base having a rectangular recess, contacts, one of which is fixed and the other of which is movable, a metal bracket for supporting the fixed contact, an insulating block on which the metal is supported, said insulating block fitting the recess in said base, a screw insulated from said base and extending through the base, the insulating block and threaded into the bracket for securing the bracket to the base.

In testimony whereof I hereunto affix my signature in the presence of two witnesses.

CHARLES THOMAS MASON.
